DESIGN FOR A BEACH CHAIR

William E. Pharo, East Orange, N. J.

Application February 7, 1939, Serial No. 82,820

Term of patent 7 years

To all whom it may concern:

Be it known that I, William E. Pharo, a citizen of the United States, residing at East Orange, county of Essex, State of New Jersey, have invented a new, original, and ornamental Design for a Beach Chair, of which the following is a specification, reference being had to the accompanying drawing, forming part thereof.

Fig. 1 is a front perspective view of the beach chair showing my new design.

Fig. 2 is a rear perspective view.

Fig. 3 is a top perspective view on a reduced scale, showing the beach chair in its reclining position.

I claim:

The ornamental design for a beach chair, substantially as shown.

WILLIAM E. PHARO.
